UNITED STATES PATENT OFFICE

154,082

DESIGN FOR A MERCHANTISE CONTAINER
OR THE LIKE

Orville W. Thraillkill, Wellington, Kans.

Application November 12, 1947, Serial No. 142,459

Term of patent 7 years

(Cl. D80—5)

To all whom it may concern:

Be it known that I, Orville W. Thraillkill, a citizen of the United States, residing at Wellington, in the county of Sumner, in the State of Kansas, have invented a new, original, and ornamental Design for a Merchandise Container or the like, of which the following is a specification, reference being had to the accompanying drawing, forming part thereof.

Figure 1 is a view in perspective of a merchandise container or the like, embodying my new design;

I claim:

The ornamental design for a merchandise container or the like, substantially as shown.

ORVILLE W. THRAILKILL.
